[57] CLAIM

The ornamental design for a console for boat, as shown and described.

DESCRIPTION

FIG. 1 is a rear elevational view of a console for boat showing my new design, the broken lines are for illustrative purposes only;

FIG. 2 is an enlarged perspective view thereof, the steering wheel is omitted for clarity of illustration;

FIG. 3 is a top plan view thereof;

FIG. 4 is a right side elevational view thereof;

FIG. 5 is a left side elevational view thereof; and

FIG. 6 is a rear elevational view thereof, showing the center panel of the console opened to expose an electronic device.

FIG. 1

FIG. 3

FIG. 6

FIG. 4

FIG. 5
